MANUAL SELECTIVE PLURAL LENGTH
TAPE DISPENSERBritton H. Doyle, Nashua, N.H., assignor to Nashua Corporation, Nashua, N.H., a corporation of Delaware
Filed Jan. 6, 1960, Ser. No. 792

2 Claims. (Cl. 226—136)

This invention concerns the dispensing of adhesively conditioned selective lengths of tape and strip material from supplies thereof for use in package sealing, labelling and such purposes, especially tape of the moisture-activated or dry-gummed type. More particularly it aims to provide in a motorized or power-driven machine of said class an improved construction and arrangement including actuating means and operator-controlled devices for obtaining selective delivery of one of a plurality of variously pre-settable tape lengths such as short and long lengths in alternation or otherwise, as appropriate for example to the girth and the length of a given package, or for different packages.

An example of a machine of the stated class to which among others the improvements of the present invention are applicable is that of the Doyle, Eisenberg and McDermott application Serial No. 845,126, filed October 8, 1959. By way of illustration the present invention is shown and described as characteristically applied to the base machine of said application.

In the drawings exemplifying one embodiment of the present invention:

FIG. 1 is a perspective view of a tape dispensing machine as a whole;

FIG. 2 is a top plan view of the same;

FIG. 3 is a right-hand side elevation of said machine with a major portion of the side gear compartment cover broken away;

FIG. 4 shows separately in side elevation an interchangeable operation control element of the invention; and

FIG. 5 is a wiring diagram.

The machine as a whole is herein sufficiently illustrated and described for an understanding of the present invention in relation to tape dispensers of the class concerned. Similarly as in the mentioned application the machine in general comprises a main frame or housing with side frames 2 on or between which are mounted the several operating elements and sub-assemblies including means for holding the main tape supplies, for feeding the tape, for pre-selecting the lengths to be delivered and for adhesively conditioning and cutting off the lengths of tape advanced for delivery to the operator.

The housing provides at the rear of the machine a holder well 3 for a roll supply of the tape to be dispensed. From the rotatably supported supply roll the tape is advanced along a path as indicated by the dotted line of FIG. 3 through guide means 4 having lower and upper walls between which the tape passes. The guide means has opposed openings for feeding engagement of the opposite faces of the tape by a driven lower feed roll 6 and an upper feed and measuring roll 7. Said driven lower roll 6 is fixed on a shaft 6a on the adjacent left-hand side frame 2 and extending into the gear housing 8 where it is drivingly connected through a train of reduction gearing with the electric motor M, FIG. 2.

The upper roll 7 is supported for bodily movement toward and from the driven roll 6. It is rotatably mounted on the forwardly extending arm of a bellcrank 7' the other arm of which is operatively engaged with an actuator 16 adapted at each operating cycle of the machine to close this normally retracted roll 7 into tape-feeding relation with the driven roll 6. Said actuator comprises a spring-loaded reciprocal rod connected at the rear end

to an actuating solenoid indicated generally at 15, FIGS. 1 to 3, and operatively engaged at the forward end with the adjacent arm of said roll-carrying bellcrank 7'. This actuator 16 also is connected with one arm of a second 5 two-arm lever, of which the other arm is connected to operate a vertical link 18, FIG. 3, by which the movable blade 20 of the tape severing means is vertically moved at the appropriate time in tape-severing coaction with a fixed blade 30. The described mechanism may be understood as generally similar to that of the application mentioned, reference also here being made to Patent No. 2,776,833 of January 8, 1957 for further showing and description of generally similar feeding, moistening and severing mechanism with which the present invention may be incorporated.

Forwardly beyond the severing means 20, 30 the tape is advanced beneath an adjustably weighted platen 19 overlying capillary moistener means (not shown) extending upwardly from a liquid reservoir 12 removably 20 held on cross supports on and between the front portions of the machine side frames 2. The level of the moistening liquid in the reservoir may be maintained in known manner from a replenishable supply in an automatic feeder flask 13 demountably located at the left side of 25 the machine, FIGS. 1 and 2.

For the purposes of the present invention the machine is equipped with a plurality of length selector elements whereby the operator may preselect any two tape lengths within an available range, such for example as up to 72 30 inches or more. Such two preselected lengths may be of any desired length value, one longer than the other, such as 18 in. and 42 in.; 8 in. and 54 in.; 24 in. and 72 in.; 30 in. and 36 in.; or whatever may be the requirements for a given taping usage. The call for tape in 35 either of two preselected and immediately available lengths, in alternation or otherwise, frequently occurs for example where a large number of packages of generally uniform size and shape is to be handled, requiring one or more relatively longer tape pieces for one dimension 40 while a shorter piece is adequate for another dimension of the package.

The selector means as illustrated, similarly as in said mentioned application, comprises two independently settable selectors respectively indicated as a whole at 60 and 600, each comprising a centrally apertured mounting disc 61 and 610 independently rotatably received on a stationary stud shaft 31 extending from the left side frame. These selectors each carry a normally-closed length-delimiting trip or knock-off micro-switch 62 and 620 45 respectively disposed with the actuator members in the path of the radial finger 46 of a rotary trip member 43 mounted to turn on the mentioned stud 31. Similarly as in the stated application the trip member 43 is provided with a clock spring for normally holding it at and 50 returning it to a zero starting position, counterclockwise in FIG. 3 wherein the finger 46 abuts a fixed stop 48 on the machine frame 2. This trip member 43 is in constantly engaged yieldable friction-driven relation with the adjacent driven gear element of a train of gearing 55 60 operatively associated with the upper feed roll 7, which latter is moved in synchrony with and by the tape as it is advanced by the feed roll pair when in feeding relation at the opposite faces of the tape. Such gear train, not necessary to show herein, serves to translate the lineal tape length measuring movement of the periphery of the upper feed roll 7 into proportionate angular movement of the trip finger 46 about the axis of the stud 31. Said 65 operatively intermediary gear train is constructed and 70 arranged to afford a substantial reduction such that the maximum tape length selection for the given machine, up to say 72 inches or more, is proportionately expressed

by not more than one full 360° rotation of the trip finger 46 in the clockwise direction about the axis of the stud 31.

It will be further understood that a tape feed operating cycle is instituted by energizing of the solenoid 15, causing the feed rolls 6, 7 to assume tape-feeding relation, herein by bodily down movement of the upper feed roll 7; similarly that de-energizing of the solenoid 15 and resultant separation of the feed rolls 6, 7 releases the described rotary tape length measuring mechanism including the trip member 43 with its trip finger 46 for return to the zero starting position under the influence of its return spring.

The two length-selectors 60 and 600 each include outer radial portions projecting beyond the gear compartment 2a and disposed for movement in one and the opposite direction along an arcuate slot between the inner portion of the latter and the removable gear compartment cover 5. Each selector has at the outer end a finger grip 63 and 630 with a length-selecting pointer 64, 640 readable against an arcuate scale 65 at the outer side face of the cover 5. Said finger grips themselves also constitute indexes readable against a similar top viewable scale 65' on the circumferential face of said gear cover. These scales are calibrated in units of tape length according to the range of the particular machine, as for example 2 inch increments, each readily subdivisible, with values indicated at 6 inch or other intervals, as shown in FIG. 1 by way of example.

The selectors are frictionally held, subject to manual shifting at the will of the operator, so that each of them will stand at whatever feed length values are selected for the given use. This may be accomplished similarly as in the mentioned application as by a friction plate 66 on the fixed stud 31 at the outer side face of the disc portion of the adjacent selector, namely the disc 610 of the selector 600 in the illustrated example, such plate having a spacer hub at the inner face of the side cover 5. A manual clamping screw 67 extending through the cover and tapped into the stud shaft 31 is adapted to apply friction-holding pressure to the selectors 60 and 600 through the mentioned washer-like friction plate 66.

From the foregoing in connection with the drawings it is apparent that either of two tape lengths is selectively available to the operator, with whatever length differential between the two may be desired for the particular use and within the range available. For the convenience of the operator the exposed manual gripping portions of the respective selectors 60 and 600 are made readily distinguishable positionally as by relating them as "rear" and "front" respectively as to location, and desirably also visually as by giving them indicia or distinctive and contrasting colors, for example blue and red. Merely by way of example the color blue is indicated for the rear or longer length selector 60 and the color red for the front or shorter length selector 600. It will be understood that the two different preset lengths of tape thus made available to the operator are each variable along the scale. At times both lengths may lie within the lower portion of the scale, at other times both may be within the upper scale range, or the shorter length may be in the lower part of the range and the longer length in the upper part. Thus the differential between the two lengths is variable preselectively to suit the particular use.

As will be apparent from the wiring diagram FIG. 5 the respective cycle-terminating trip switches 62 and 620 of the respective selectors are adapted to serve, alternatively, as the active cycle-terminating instrumentality, by being placed in series with the solenoid 15. The knock-off switch which is to be active for any given feed cycle is determined by the operator when starting the operation, by selecting as between the "blue" or relatively long length cycle and the "red" or relatively short length cycle. Two separate manual cycle-starter elements, later

to be described in more particular, are provided at the selective disposal of the operator.

For the dual length selection and attendant dual feed cycling with which the present invention is concerned 5 the control circuits as diagrammed in FIG. 5 include provision herein associated with a leads junction box 300 on the machine frame, whereby the shorter-length or "red" selector 600 stands with its switch 620 normally closed in readiness for length-measured cycle-stopping control of a shorter-length feed cycle to be started by actuation by the operator of a shorter length or "red" switch 705 to be described; whereby also the longer length or "blue" cycle terminating at and by the normally closed cycle-stopping switch 62 of the "blue" selector 60 stands readied to function in a longer length cycle to be started by a "blue" starter switch 70 to be described; and whereby further the effect of the shorter length or "red" cycle-stopping trip switch 620 is automatically cancelled by said "blue" starter switch 70 when a longer-length or "blue" cycle is called for by the operator.

Such cancelling or by-passing of the shorter "red" cycle-ending control during a longer "blue" cycle is accomplished as by installing on the machine a "Comar" or equivalent relay unit 625 having a normally open magnet-operable switch 626, FIG. 5, with dual circuit leads connected through a four-wire cord 628 to a four-terminal plug 629 receivable at the machine junction box 300. It is understood with reference to FIG. 5 that the terminals numbered 1, 2, 3, 4 of plug 629 match respectively with the like numbered leads 1, 2, 3, 4 of the junction box when the plug-together connection is made thereat. The same applies also to the other detachable plug-and-socket type connections of FIG. 5, namely the terminals 2, 3, 5 of the dual cycle-starter switch cords 72 and 720 with plug 725 having reception at the outlet box 100, on the left-hand machine frame 2 and at the right portion of FIG. 5 and the terminals 1, 2, 3, 4 of the connector leads of the cycle-halting switches 62 and 620 received at the machine receptacle 200 seen in FIG 3 and at the left portion of FIG. 5. For the dual length selection assembly with which the present invention is concerned, noting particularly FIG. 5, the connector cable 72, 720 for the two manual switches 70 and 705 is applied by plug 725 to the outlet box 100, the relay connection 629 is applied at the junction box 300, and the two selectors 60 and 600 have their connector cable 69 applied by plug 69p to the receivable 200 on the machine.

As stated, the tape feed cycle for each length is separately controllable by the operator, selectively, each by its own cycle-starting switch.

As a dominant feature of the present invention such cycle-starting switch means is operatively installed, demountably and interchangeably, directly upon the machine frame, at a top front portion thereof, in a position to be readily accessible to the operator from either the front or a side of the machine. The two separate switch actuators respectively designated as a whole at 70 and 705 are herein disposed in relatively close proximity to the length-selectors 60 and 600 and the path of length-selective movement thereof. Further their relative positional location and arrangement is such as to correlate them respectively to the manual operating portions 63 and 630 of said respective selectors. Thus in the illustrated example the starter switch 70 for the "blue" or longer length tapes is located nearer the rear of the machine, corresponding to the rear position of the "blue" or longer length selector 60. Correspondingly the starter switch 705 for the other or shorter tape lengths is placed more forwardly and herein lower on the machine frame, generally adjacent and matching the relative position of the "red" or shorter length selector 600. This construction and arrangement of the pair of cycle-starter switches for the different lengths has provision to be of unique utility in the use of the tape dispenser machine by physically handicapped operators and particularly blind persons and those with severely restricted vision. Upon familiarizing

themselves with the operation of the machine and the location of the easily accessible rear and front selectors 60 and 600 such operator's hand in passing from setting of the length selectors readily and naturally follows to the corresponding cycle starter switch closely adjacent the selectors and in the same corresponding fore and aft relation longitudinally of the machine and with respect to the direction of selective adjustment of the selectors. For general use the two starter switches 70 and 705 also are markedly visually distinguished as by the application of distinctive colors to the pushbutton or other manual engaging portions 71 and 715 respectively of the switch. Such distinctive color or other marking of the switches is correlated to that of the finger pieces 60 and 600 of the selectors and in the illustrated example by coloring blue the rear button 71 and for the "blue" or longer length feed cycling and red for the shorter length feed cycling, similarly as for the respective selectors.

In the illustrated example such construction and arrangement for the starter switch installation is accomplished by providing the right-hand machine frame 2, in the region of the arcuate flange 2' of the side cover housing with a segmental opening adapted for the reception of a demountable and interchangeable flange segment or arcuate panel 250, FIGS. 1 and 2 and shown separately in FIG. 4. Such switch panel comprises a plate body 251 dimensioned to fit the opening on the side frame and being bounded at the ends and at the inner longitudinal edge by an elevated and projecting flange 252 for seating of the switch plate upon the margin of the frame opening. At the inner convex face the plate body 251 is formed with vertical flanges such as 253, 254 for anchoring of the plate.

At the appropriate locations lengthwise of the arcuate plate 250, such as to afford the above described location for the respective switch, the plate is apertured for reception of mounting nipples or the like on the bodies of respective microswitches 70 and 720. The mounting nipples extend through the openings and are anchored to the plate as by inside and outside locknuts such as 73, 730 threaded onto the nipples. The manual switch operating elements proper, shown as pushbuttons 71, 715, are depressibly mounted in the switch attaching nipples and normally held elevated in readiness for operation by manual depression, through the self-contained spring means associated with the circuit make and break element of the microswitches themselves. These latter are of the normally open type.

Assuming the "red" and "blue" selectors 600 and 60 respectively set for the desired two different tape lengths, automatic feed, moistening, cut-off and delivery of the shorter tape length is had by manual closure of the "red" cycle-starter switch 705. When the rotary measuring projection 46 comes opposite and engages the actuator roll 622, see FIG. 3, of the "red" arm trip switch 620, said normally closed switch is thereby opened and the feed cycle halted by deenergizing of the actuator solenoid 15, with stopping of the motor and return of the holding switch 150 to normal open position attendant on the cut-off operation under the return movement of the actuator 16 to normal released position.

Delivery of the selected longer tape length is had by operator closure of the "blue" cycle-starter switch 70. The normally open relay switch 626 is thereby closed, along with the holding switch 150, and through the illustrated relay circuits and lead connections through the junction box 300 the "red" trip switch 620 is in effect shunted out or cancelled from the then active circuits. Hence the movement of the driven measuring projection 46 past the "red" trip switch 620 although engaging and moving the switch actuator roll 622 has no cycle-halting effect thereat and the feed cycle continues on until said projection 46 engages and trips the "blue" arm trip switch

62. Thereby the tape feed is halted at the longer tape length corresponding to the location of said switch 62 under the particular selective setting of the "blue" selector 60.

5 From the foregoing description in connection with the drawings it is apparent that the invention provides a power-driven machine of the class described capable of supplying at the will of the operator either of two different tape lengths, each of them pre-settable within the 10 available range, in a cycling operation in which the elected tape length is fed, measured, moistened, cut off and delivered in adhesive condition for use, together with separate cycle-starter manual controls constructed, arranged and relatively located upon the machine so that each is 15 inherently and naturally correlated respectively with the length selector means for the respective tape length to facilitate and assure selection and cycling feed of the desired tape length whether by visual or locational determination and manual engagement of the correct cycle-starter 20 device by the operator.

My invention is not limited to the particular embodiment thereof illustrated and described herein, and I set forth its scope in my following claims.

I claim:

- 25 1. In a tape dispensing assembly comprising a base machine having a frame,
a support thereon for a supply roll of tape,
separable feed rolls,
an electrically operated actuator for closing and opening
30 the rolls to and from tape feeding relation,
tape cut-off means and operating connection therefor
with the actuator,
a motor operable intermittently to drive one of the
35 feed rolls,
measuring means connected to move with one roll pro-
portionately to the tape length fed,
the combination therewith of
(a) a plurality of length selectors variably positionable
40 in the path of the measuring means at any selected
individually different tape lengths in the available
range,
(b) there being a relatively rotatably disposed cycle-
45 halting trip switch and switch tripper means for each
length selector actuatable by the measuring means
upon length measuring movement thereof corre-
sponding to the length selections of said selectors,
(c) a like plurality of operator actuatable starter
50 switches,
(d) and a corresponding plurality of control circuits
each containing said motor, said actuator and the
starter switch and the trip switch means correspond-
ing to one length selector,
(e) said starter switches mounted on the machine ac-
55 cessibly to the operator,
(f) and the machine including said selectors and
starter switches being constructed and arranged with
provisions operatively and positionally differentiating
each selector and each starter switch from the
60 other as to relative tape lengths responsive thereto
and for correlating the particular starter switch with
the corresponding length selector,
(g) said trip switch means being aligned for suc-
65 cessive engagement by the moving measuring means,
(h) and the control circuit for a longer length selector
and starter switch including therein relay means sub-
ject to the starter switch of said circuit to render
inoperative the trip switch of the circuit for any
70 shorter length selector during operation under the
control of the longer length selector,
(i) and whereby one and the same given selector
75 effects delivery always of a relatively shorter tape
length and another given selector effects delivery
always of a relatively longer tape length.

2. A tape dispensing assembly according to claim 1
 (a) wherein the machine frame is provided at an operator-facing location adjacent the path of the selective setting of the length selectors with a demountable frame-conforming panel,
 (b) and the starter switches are mounted on said panel and present operating members such as buttons readily distinguishably accessible to the operator,
 (c) said starter switches having electrical leads terminating in a detachable-type connector and said machine frame carrying an outlet receptacle connected in the circuit of the motor and of the actuator and adapted to receive said starter switch connector,
 (d) and said trip switch means of the selectors also having connection leads extending to a detachable-

5
 10

type connector and said machine frame carrying a further junction receptacle connected into the motor and actuator circuit and adapted to receive said trip-switch connector,

- (e) whereby the starter switches together with said selector trip means and connectors therefor are constituted as a detachable sub-assembly readily demountable from the dispensing assembly for substitution by other control means.
